UNITED STATES PATENT OFFICE.

EMILE MINETTO AND JOHN MINETTO, OF NEW YORK, N. Y.

DESIGN FOR A GAME-BOARD.

SPECIFICATION forming part of Design No. 28,673, dated May 17, 1898.

Application filed March 2, 1898. Serial No. 672,330. Term of patent 3½ years.

To all whom it may concern:

Be it known that we, EMILE MINETTO and JOHN MINETTO, citizens of the United States, residing at the city of New York, in the county 5 of New York and State of New York, have invented and produced a new and original Design for Game-Boards, of which the following is a specification, reference being had to the accompanying drawings, which form a 10 part thereof.

In the drawings, Figure 1 is a plan view of a game-board, showing our new design; and Fig. 2 is a sectional view taken on the line 2 2, Fig. 1.

15 As shown in the drawings, the leading feature of our design consists of a flat board or base A, surrounded by an upright edge or flange a, and having centrally upon its top face a representation of cannon-barrels b, 20 radially arranged, similar representations of cannon-barrels c being arranged at the corners and the top surface of the board being provided with a series of recesses or depressions d, relatively arranged with respect to 25 said central and corner representations of cannon-barrels. The base or board A is rectangular in contour or outline and is surrounded on all sides with the edge or flange a, which latter projects upwardly beyond its 30 top surface. The central series or representa-

tions of cannon-barrels b extend radially from a circular space e, arranged at the center of the top surface of the board, and centrally in said circular space e is arranged a recess or depression f. The representations of cannon-barrels c at the corners of the board extend from approximately V-shaped or pointed corner spaces g, which represent the bows of ships, and the corner representations of cannon-barrels c extend in a direct line with relation to the opposite cannon-barrels b of the central series. The recesses or depressions d are arranged in series at the opposite ends of the board and between the respective representations of the cannon-barrels c and b, as 40 shown.

Having fully described our invention, we claim as new and desire to secure by Letters Patent—

The design for a game-board, substantially 45 as herein shown and described.

In testimony that we claim the foregoing as our invention we have signed our names, in presence of the subscribing witnesses, this 21st day of February, 1898.

EMILE MINETTO.
JOHN MINETTO.
